CLAIM

The ornamental design for a vaporizer cartridge, as shown and described.

DESCRIPTION

FIG. 1 is a left side, front, and top perspective view of a vaporizer cartridge of our design;

FIG. 2 is a right side, front, and bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dash-dash broken lines illustrate portions of the vaporizer cartridge that form no part of the claimed design.

1 Claim, 8 Drawing Sheets
